UNITED STATES PATENT OFFICE.

RALPH C. BANGS, OF CRANSTON, RHODE ISLAND, ASSIGNOR OF ONE-FOURTH TO
PHILIP H. CADBY, OF PROVIDENCE, RHODE ISLAND.

GARMENT-HANGER.

1,228,636.

Specification of Letters Patent.

Patented June 5, 1917.

Application filed April 16, 1915. Serial No. 21,804.

To all whom it may concern:

Be it known that I, RALPH C. BANGS, a citizen of the United States, and resident of Edgewood, city of Cranston, in the county of Providence and State of Rhode Island, have invented certain new and useful Improvements in Garment-Hangers, of which the following is a specification.

This invention relates to garment hangers of the class designed more especially for the support of trousers, skirts or other wearing apparel to retain the garments in proper shape without creases or wrinkles when not in use.

15 The object of this invention is to provide such a rack or hanger having a plurality of individual bars coöperating with pivoted clamping members for automatically gripping and retaining a garment between them, whereby the end of the garment may be engaged and the greater the weight of the garment the tighter the grip upon the same.

A further object of the invention is to 25 provide a hinge whereby it may be supported in a horizontal position to facilitate positioning the garment therein, which hinge also permits the rack to be swung down into a vertical position when desired, to take 30 up the minimum amount of space.

With these and other objects in view, the invention consists of certain novel features of construction, as will be more fully described, and particularly pointed out in the 35 appended claims.

In the accompanying drawings:

Figure 1— is a perspective view of the hanger showing the frame in horizontal position and a plurality of garments hung 40 therein.

Fig. 2— shows the frame partly in section with one of the sides removed and as swung down on its hinge to hang in a vertical position.

45 Fig. 3— shows a portion of the frame in section and set in a horizontal position illustrating the action of the clamping members against the cross-bars to grip and retain the garments.

50 Fig. 4— is a plan view of a portion of the frame partly in section showing the clamping members pivotally mounted therein.

Fig. 5— is a perspective view showing one form of clamping member comprising a 55 wire loop with its ends offset from the body

portion thereof to form pivots on which the member swings.

Fig. 6— shows the hinged portion of the frame as moved outward from the base to bring this pivot into the offset portion 60 whereby the frame may be swung down into vertical position to be suspended on the hinge.

Fig. 7— illustrates the hinge portion as moved downward to bring the pivot out of 65 the off-set portion of the slot whereby its inner and lower edge is moved into contact with the base member to support the frame in horizontal position.

Referring to the drawings 10 designates 70 the frame portion of my improved hanger which may be formed of any desired material and in any desired shape, but the same is herein illustrated as being formed of wood and in a hollow rectangular shape 75 having two side members 19 and 20 and two end members 21 and 22, said frame being provided with a plurality of transverse cross-bars 11 placed at intervals throughout the length of the frame. In each space 12 between these bars, I have mounted a clamping member 13. This clamping member may be made in any suitable form, the essential feature being that it must have a clamping edge 14 to swing toward its adjacent bar to 80 bite the garment against the bar. I have, however, shown this clamping member as formed of wire, see Fig. 5, having its end portions 17 bent back at substantially right angles with the gripping edge 14 thereof 85 and the extremities of the wire then turned outward forming pivots 15 and 16 which engage corresponding recesses 18 in the opposite side bars of the frame, whereby when the gripping or binding member is thus pivotally mounted in position in the frame its 90 engaging edge 14 coöperates with the wall of an adjacent cross-bar to bind and hold the garment between them the extent of the biting action being in proportion to the 100 weight of the garment.

Another feature of this invention is the provision of means whereby the rack may be held or supported in a horizontal position to facilitate placing of the garments 105 therein. This function may be accomplished in many different ways but in order to do this in a simple manner, I have formed a pair of hinge members 23 and 24 which may be secured by screws or other suitable 110

means to a base 25, each member having an outwardly turned flange 26. I have also provided hinged plates 27 and 28 secured by screws or otherwise to extend beyond 5 the end of the rack member and extend into engagement with aforesaid fixed hinged members 23 and 24. Each of these plates as best illustrated in Figs. 6 and 7 is provided with an elongated slot 29 which is 10 off-set at its lower end 30 in the direction of the base-plate, whereby when it is desired to support the hanger in a horizontal position the hinge member is pressed downward as shown in Fig. 7 bringing the hinge pivot 15 at the upper end of the slot which causes the edge 31 of the rearwardly extending portion, to engage the base and so prevent the frame from swinging downward, but when it is desired to release the frame and permit it to drop to a vertical position the hinged plates are raised bringing the pivot 20 down into the off-set portion of the slot thereby moving the hinge plates outward into position illustrated in Fig. 5, whereby 25 the edge 32 is permitted to swing past the base plate and permit the frame to drop. In operation the device is preferably formed complete with the base-board 33 to which the hinged members are connected. 30 This base-board member may then be attached to the wall or to the inside of a clothes press door and when it is desired to hang garments in the rack the same is raised to a horizontal position and the hinged end 35 moved downward into position illustrated in Fig. 7 which causes the rack to remain in that position as long as desired. In hanging a garment in the rack it is only necessary to raise one of the gripping members 40, 13, pass the ends of the trouser legs *a* up through one of the spaces between the wall of the adjacent cross-bar and the gripping edge 14 of the binding member, then by releasing the latter it falls into engagement 45 with the surface of the fabric and when a pull on the garment is exerted due to its weight the tighter is the grip between the binding member and the wall of the bar. In other words, the grip is automatically 50 applied and in proportion to the weight or pull of the garment.

One advantage in a device of this character is that when trousers are held in the rack they may be gripped close to the end of the 55 leg portions where the crease, if any were made, would not show. In other devices of this character the legs of the trousers are obliged to be folded over the hanger bar

which brings a crease in the most exposed portion of the garment which effect is quite 60 undesirable. Then again in supporting a skirt, it may be hung by the binding edge and in this way no crease will be made in the exposed part of the fabric. After the desired number of garments have been hung 65 in the rack, it is only necessary to raise the hinged end which permits the frame to fall to a vertical position as illustrated in Fig. 2. I have shown and described one form of 70 garment hanger but the exact shape is not essential and I desire to be understood as not limiting myself to the particular formation of the parts described and illustrated herein.

I claim:

1. A garment hanger comprising a frame provided with side bars connected by transverse permanently spaced partitions, and gravity operating clamping members pivotally attached to said side bars near the 80 lower edges thereof, and adjacent a transverse partition, and each extending diagonally upward and having a free longitudinal edge coöperating with one side of a partition spaced from the first mentioned partition, to form a garment supporting clamp. 85

2. A garment hanger comprising a frame provided with side bars connected by transverse permanently spaced partitions, and bent wire clamping members having offset 90 ends pivotally engaging said side bars near the lower edges thereof, and adjacent a transverse partition, and each having a straight body portion coöperating with one side of a partition spaced from the first 95 mentioned partition, to form a garment supporting clamp.

3. A garment hanger comprising a frame provided with side bars connected by transverse permanently spaced partitions, gravity operated clamping members coöperating with said partitions to form garment supporting clamps, ears attached to said side walls and having transverse slots provided with offset ends, and a supporting 100 member provided with pins entering said slots, whereby said frame may be selectively supported in a vertical or horizontal position. 105

In testimony whereof I affix my signature 110 in presence of two witnesses.

RALPH C. BANGS.
